UNITED STATES PATENT OFFICE.

JOSEPH K. WOZNICA, OF DETROIT, MICHIGAN, ASSIGNEE TO TRAUB MANUFACTURING COMPANY, OF DETROIT, MICHIGAN.

DESIGN FOR A WEDDING-RING.

48,213.

Specification for Design.

Patented Nov. 23, 1915.

Application filed September 25, 1915. Serial No. 52,735. Term of patent 14 years.

To all whom it may concern:

Be it known that I, JOSEPH K. WOZNICA, a subject of the Emperor of Austria-Hungary, residing at Detroit, in the county of Wayne and State of Michigan, have invented a new, original, and ornamental Design for Wedding-Rings, of which the following is a specification, reference being had to the accompanying drawing, forming part thereof.

In the drawings, Figure 1 is a perspective on a large scale of a wedding ring embodying my new design. Fig. 2 is a transverse section of the ring.

I claim:

The ornamental design for a wedding ring, as shown.

JOSEPH K. WOZNICA.
